RIVETING-MACHINE.

1,271,276.

Specification of Letters Patent. Patented July 2, 1918.

Application filed April 3, 1917. Serial No. 159,575.

To all whom it may concern:

Be it known that I, JULIUS N. CAYO, a citizen of the United States, residing at Gary, in the county of Lake and State of Indiana, 5 have invented new and useful Improvements in Riveting-Machines, of which the following is a specification.

This invention relates to metal forging, and more especially to power hammers 10 which are hand-operated; and the object of the same is to produce a riveting machine wherein the hammer is caused to deliver rapid strokes to work overlying the anvil and the force of the blows may be instantaneously adjusted, or the hammer can be 15 thrown out of action without stopping the rotation of the power wheel which carries the cams.

These and other objects are carried out 20 by the mechanism hereinafter more fully described and claimed, and as shown in the drawings wherein:

Figure 1 is a side elevation of this machine complete.

Fig. 2 is a detail of the face of the hammer.

A suitable table 1 is mounted on legs or standards 2 and supports bearings 3 in which at 4 is journaled the shaft of a wheel 5 30 which in the present instance is rotated constantly by a belt 6 leading downward from a source of power overhead and not necessary to illustrate. This may be called the cam-wheel, and it is provided with a series 35 of pins 7 in its side face which constitute the cams. The anvil 9 is indicated as supported at the front end of the table.

Another standard at about the midlength of the table, constitutes a fulcrum 10 for 40 the hammer 11 whose forward end carries the hammer head 12 which coacts with and strikes upon the face of the anvil 9. As seen in Fig. 2 this head may have a plurality of faces, and the anvil will be wide enough 45 to accommodate all of them or may itself have a plurality of faces. I intend to use this machine for riveting, in which case these faces are shaped accordingly; but I do not wish to be limited in this respect as 50 the machine may be used for any purpose to which it is adapted. The forward arm of the hammer is rather longer than its rearward arm, and a tension spring 13 of considerable strength leads downward there- 55 from, through a hole or aperture 14 in the

table, and is connected at 15 with a treadle 16 which is pivoted at 17 at its rear end to one of the rear legs and has a foot piece 18 standing within reach of the operator at the front of the machine. When now pressure is placed on the foot piece, the treadle puts tension on the spring 13, and the latter naturally draws the front arm of the hammer downward, but when pressure is removed from the foot piece the front arm of the hammer sustains the weight of the 60 spring and the weight of the treadle.

The rear and shorter arm of the hammer preferably has a wear plate 20 attached thereto by screws or bolts 21 and provided 70 with a tongue 22 at its rear end projecting alongside the wheel 5 and within the path of the pins 7, and therefore when the wheel rotates in the direction of the arrow these pins successively strike the tongue and depress the wear plate and the rear arm of the hammer. A suitable stop 23 prevents its 75 excessive depression. The numeral 24 designates a relief spring connecting the rear arm of the hammer with the table 1 at a 80 suitable point in the rear of the fulcrum 10, and the strength of this spring is such that it will overcome the weight of the front arm and the forward spring 13 and treadle 16.

It follows, therefore, that when the operator removes his foot from the foot piece 18, the front arm of the hammer rises and the rear arm descends and the wear plate moves out of the path of the pins on the cam wheel so that the latter rotates idly 85 thereafter and the hammer delivers no blows. On the other hand, when the operator depresses the treadle he overcomes the force of the release spring and the rotation 90 of the cam wheel forces the pins to engage 95 the wear plate as will be clear. Each pin bears down on this plate and tilts the front end of the hammer upward, and then when it passes off the plate the tension spring causes the front arm of the hammer and 100 its head to descend, and the face of the head delivers a blow onto the anvil or on the work laid thereupon. The force of this blow is regulated by the tension applied to the spring 13, and this tension is immediately adjustable by the operator who has it under the control of his foot. I have 105 successfully used this machine to deliver as high as sixteen hundred blows a minute, but it can be run more rapidly or more 110

slowly with equal success. It is not essential that the hammer have a plurality of faces, although obviously more rapid work can be done with a plural-faced hammer than 5 with one having but a single face.

While I have shown the power as applied to the wheel 5 by means of a belt, I do not wish to be limited in this respect. The parts 10 are of the desired sizes, proportions, and materials; and changes in details within the scope of the claim may be made without departing from the principle of the invention. Also I do not wish to be limited to the exact springs shown and described herein except as required by the claim, as it is obvious that their mechanical equivalents 15 could be employed.

What I claim as new is:—

20 In a riveting machine, the combination with a table mounted on legs and having bearings at its rear end, an anvil at its front

end, and a fulcrum between these elements, a power driven wheel mounted in said bearings and having pins projecting from it, and a treadle pivoted to one of the rear legs 25 and underlying the table-top; of a hammer pivoted near its rear end in said fulcrum, a head at its front extremity overlying said anvil, a spring connecting its front portion adjacent said head and the forward portion 30 of said treadle, an upstanding stop in the table in rear of said fulcrum, a wear plate carried by the rear end of the arm and successively struck by said pins, and a relatively weak spring connecting said rear end 35 to the table and of sufficient force to raise the front end of the hammer and its head and said treadle and its spring when the latter is not under tension, for the purpose set forth.

40 In testimony whereof I affix my signature.
JULIUS N. CAYO.
